UNITED STATES PATENT OFFICE.

JAMES E. WHITACRE, OF ROCKFORD, ILLINOIS.

PENCIL-SHARPENER.

1,095,612.

Specification of Letters Patent.

Patented May 5, 1914.

Application filed December 26, 1912. Serial No. 738,735.

To all whom it may concern:

Be it known that I, JAMES E. WHITACRE, a citizen of the United States, residing at Rockford, in the county of Winnebago and 5 the State of Illinois, have invented certain new and useful Improvements in Pencil-Sharpener, of which the following is a specification.

The object of this invention is to construct 10 a pencil sharpener of an inexpensive and simple design and in which the blade or knife shall be easily adjusted.

A further object is to construct the pencil 15 sharpener of such a form that it may be applied to small stationary and desk articles, such as, paper-weights, blotter-pads, desk-trays, etc.

In the accompanying drawings: Figure 1 is a plan view of the pencil sharpener with 20 a portion of its top broken away. Fig. 2 is a section on the line *a—a* of Fig. 1 showing the method of sharpening the pencil. Fig. 3 is a section on line *b—b* of Fig. 1. Fig. 4 is a detail of the spring for contacting the knife blade.

The base plate 1 forms a support for the concave shell 2, the shell being simply held in a fitting engagement with the base, and the two members forming a desirable receptacle for the shavings cut from the pencil. At the central portion of the top of the concave shell is an opening 3, at the two sides of which are formed the upturned guides 4.

35 A knife blade 5, being yieldable in construction and having a cutting-edge at both of its ends, is adjustably held to the under face of the concave shell by the adjusting screw 6 in such a manner that one of the cutting-edges is located in the opening 3 and projects slightly above the top of the shell. A spring plate 7 lies intermediate the blade 5 and shell 2, its two opposite ends resting on the shell and a downturned 45 central strip 8 engaging the lower end of the blade 5.

As is seen in Fig. 2, blade 5 may pivot from the point 9 and the spring plate 7 with the coöperation of the spring quality 50 of the blade itself and the screw 6 holds the blade yieldable in position, while the screw 6 lying between the pivotal point and yieldable support, varies the tension of said support thereby pivoting the blade and raising or lowering the height of the cutting-edge 55 located in the opening 3.

In sharpening a pencil, the base is held fixed and a pencil drawn over the opening of the shell, thus engaging the projecting knife edge and resulting in the cutting of 60 shavings from the pencil longitudinally, the repeated action of which results in a very desirable sharpened point on the pencil.

It will be seen that with the convexity of the face of the shell, a free easy movement 65 can be given the pencil, the pencil being held from lateral displacement by the upturned edges 4. It will also be noted that the cutting-edge of the blade is yieldable and is depressed when a cut is attempted 70 too large for its capacity, or when the quality of the wood is too hard; also the blade may be reversed when one of the cutting-edges becomes dull and the blade is easily adjustable by removing the shell and 75 adjusting the screw 6 as above indicated. It will be noted that a shell of this type, carrying the sharpening means, may be applied to many desk and stationary articles, that is, to the top thereof, to good advantage 80 because of the association of such articles with the employment and use of pencils.

I claim as my invention:

1. A pencil sharpener comprising a convex shell adapted to be detachably held in 85 a base, the base and shell forming a shaving receptacle, the shell having an opening in its convex surface, pencil sharpening means carried on the inner side of the shell comprising, a blade having a cutting-edge located in the opening, the blade being in contact with an edge of said opening, means for yieldably depressing the other end of blade, and means for adjusting the portion of the blade intermediate said contact and depression points to vary the position of the cutting-edge in the opening.

2. A pencil sharpener comprising a convex shell having an opening therein, a blade having a cutting-edge located in the opening and the blade being in pivotal contact with the shell at a point adjacent said opening, a spring engaging the end of the blade opposite said cutting-edge end and lying intermediate the blade and shell, and an adjusting screw connecting the blade and shell and located at a point of the blade intermediate the pivotal point thereof and the spring engagement and adapted to vary the position of said cutting-edge in the opening.

3. A pencil sharpener comprising a convex body portion having an opening in its

surface, a blade disposed at the inner side of said convex portion with a cutting edge at one end of the blade resting in contact with a pivot point adjacent an edge of said opening and the blade disposed chord like spanning an inner convex portion of the body with its opposite end portion bearing against an inner surface of said body, and an adjusting screw connecting the chord portion of said blade whereby said chord portion may be adjusted to and away from the convex body portion to vary the position of the cutting edge in said opening.

4. A pencil sharpener comprising a body having a convex shell portion with an opening in the shell intermediate the ends of curvature thereof, a blade disposed chord like spanning an inner side of said convex portion, having a cutting edge end thereof located in said opening and having its opposite end portion in a thrust against an inner surface of the body, and an adjusting screw connecting the chord portion of said blade whereby said chord portion may be adjusted to and away from said convex shell portion

to vary the position of the cutting edge in said opening.

5. A pencil sharpener comprising a convex shell adapted to be detachably held in a base, the base and shell forming a shaving receptacle and the shell having an opening in its convex surface, pencil sharpening means carried at the inner side of the shell, comprising, a blade having a cutting-edge located in the opening and having a portion of the blade body in contact with the shell at a point adjacent an edge of said opening, a contact for the end of the blade opposite its cutting-edge end, and means for adjusting the portion of the blade intermediate said contact points to vary the position of the cutting-edge in said opening.

In testimony whereof I have hereunto set my hand in presence of two subscribing witnesses.

JAMES E. WHITACRE.
